UNITED STATES PATENT OFFICE.

HARRY J. BLACKBURN, OF AKRON, OHIO.

DESIGN FOR A GRAVE-MARKER.

SPECIFICATION forming part of Design No. 34,589, dated May 28, 1901.

Application filed April 24, 1901. Serial No. 57,349. Term of patent 7 years.

To all whom it may concern:

Be it known that I, HARRY J. BLACKBURN, a citizen of the United States, residing at Akron, in the county of Summit and State of Ohio, have invented and produced a new and original Design for Grave-Markers, of which the following is a specification, reference being had to the accompanying drawings, forming a part thereof.

10 In the drawings, Figure 1 is a plan view of my design, and Fig. 2 a sectional view taken on the line $x-x$ of Fig. 1.

As shown in the drawings, my design consists, primarily, of a circular metallic plate having a bead A about the outer edge of one face and a concentric bead B within, leaving an annular space between them. Within the inner circle is an eagle C, with outspread wings, with his claws grasping cross-flagstaffs

D and E, the front one bearing the United States flag and the other the Cuban flag. Above the head of the eagle and extending beyond the wings in each direction is a row of stars F. The wings of the eagle extend over the bead B of the inner circle. A perforated lug is placed on the back.

Having described my invention, what I claim as new, and desire to secure by Letters Patent, is—

The design for a grave-marker, as herein shown and described.

In testimony whereof I have signed my name to this specification in the presence of two subscribing witnesses.

HARRY J. BLACKBURN.

In presence of—

C. E. HUMPHREY,
MAUDE ZWISLER.
